6 Sheets-Sheet 1

A geological cross-section diagram. At the top, a dashed line labeled 'D' is shown above a layer labeled 'E'. A vertical arrow points downwards from 'E' to a layer labeled 'c'. To the left, a layer labeled 'J' is shown above a layer labeled 'm'. A bracket is placed under the 'm' layer. To the right, a layer labeled 'F' is shown above a layer labeled 'F''. A vertical arrow points upwards from 'F' to a layer labeled 'c'. The layers are depicted with different hatching patterns: 'D' and 'E' have vertical lines, 'c' has diagonal lines, 'J' has horizontal lines, 'm' has small dots, and 'F' and 'F'' have horizontal lines.

UNITED STATES PATENT OFFICE.

DONALD VIVIAN HOTCHKISS, OF HELENSBURGH, SCOTLAND, ASSIGNOR TO THE HOTCHKISS HYDRAULIC PROPELLER COMPANY, LIMITED, OF LONDON, ENGLAND.

PROPELLION OF VESSELS.

Application filed July 10, 1920. Serial No. 395,224.

To all whom it may concern:

Be it known that I, DONALD VIVIAN HOTCHKISS, of Green Point Cottage, Princes Street, Helensburgh, Scotland, a subject of the King of Great Britain, have invented certain new and useful Improvements in the Propulsion of Vessels, of which the following is a specification.

This invention relates to the fluid propulsion of ships, aircraft and the like.

Fluid propellers have already been proposed for the propulsion of ships but these have not proved satisfactory mainly because of the high frictional losses set up due to the formation of eddy currents, and to the conversion by centrifugal action of velocity head into pressure head.

The object of the present invention is to provide an improved method of and means for the fluid propulsion of ships, aircraft and the like whereby such losses will be reduced to a minimum. A further object is to provide a fluid propeller specially adapted for use in vessels intended for service in shallow or weedy waters.

To the attainment of these objects the invention consists primarily in propelling the vessel by the action of an induction vortex which, when the vessel is in motion, is fed by streams of fluid entering only in the direction of rotation at the sides and between the centre and circumference of the vortex, the streams being caused to merge finally into a single stream discharged tangentially at the circumference. By the term "vortex" as herein used I mean a gyrating mass of fluid the particles of which, in a single circuit, pass from orbits of less to orbits of greater diameter, acceleration of the fluid taking place gradually during the circuit from entry to discharge.

The invention further consists of a fluid propeller comprising a casing, preferably elliptical in cross section, and an impeller mounted for rotation therein said casing having inlet openings in the opposite sides disposed between the centre and the circumference and also having at least one tangential discharge opening in the peripheral wall in the same radial plane as said inlet openings, whereby, when the propeller is fitted in the bottom of a vessel with the inlet and discharge openings exposed to the surround-

ing fluid medium and when the impeller is rotated, a fluid vortex will be formed.

It further consists of a fluid propeller, as aforesaid, having means whereby the propeller can be made reversible whilst the direction of rotation of the impeller remains unaltered.

It further consists in the novel construction, combination and arrangement of parts substantially as herein described with reference to the accompanying drawings and pointed out in the appended claims.

In order that the invention may be clearly understood explanatory drawings are hereto appended whereon two constructions of the propelling apparatus suitable for water craft are shown by way of example.

Fig. 1 is a diagram illustrating the action of the apparatus.

Fig. 1^a is a longitudinal section showing an hydraulic propelling apparatus fitted in the shell of a ship at the bottom thereof.

Fig. 2 is an inverted plan view of the apparatus, Fig. 1.

Fig. 3 shows a pair of hydraulic propellers as fitted in the ship one on each side of the keel.

Fig. 4 is a view of the apparatus, Fig. 1, but arranged so as to give a reverse drive.

Fig. 5 is a view of an adaptation of the hydraulic propelling apparatus suitable for small craft, such as motor boats or the like. The apparatus is shown in longitudinal section.

Fig. 6 is a vertical cross section on line 6—6, of Fig. 5.

Fig. 7 is a sectional plan on line 7—7, of Fig. 5.

Fig. 8 is a view of the impeller.

On the drawings the same reference letters wherever repeated indicate the same or similar parts.

Referring first to Fig. 1, it will be seen that a drum B constructed of any suitable material impervious to chemical action from the fluid concerned, is provided. This drum, which may be of rectangular or preferably slightly elliptical cross section, is provided with means, such as a paddle wheel or impeller A, by the aid of which a vortex may be formed and maintained having the same axis as that of the drum.

A single segment, including a portion of

the periphery of the drum, is removed so as to leave an opening C which forms both the inlet and outlet. D. E. are the two inflowing or feeding streams of fluid and F the outflowing or discharge stream which, in section, appears as at F¹. The impeller is rotated in the direction of the arrows x, y. In the arrangement preferred the drum is installed in the ship so that the portion containing this opening projects through the sides or bottom of the hull the fluid being caused to flow into the drum at a point between the periphery, and the centre, and not at a point nearer the periphery both entrance and delivery being in the horizontal plane, or substantially so. The drum may be given any convenient proportions suitable to the ship it is desired to propel, the greatest breadth consistent with efficient operation being about equal to the diameter and the most generally efficient proportions being found when the breadth is equal to half the diameter.

In order to encourage the flow of fluid into the drum when the ship is at high speed, and at the same time to reduce the head resistance offered to forward motion by the portion of the drum projecting outside the ship's hull, a stream line body is provided. This is arranged so that the region of positive pressure at the quarters is coincident with the portion of the opening in the drum forming the intake. The fluid, therefore, is induced to enter the intake portion of the opening by means which are supplementary to the action of the vortex.

The fluid, entering the drum, performs a double function, (a) to supply and feed the vortex so as to maintain a constant discharge, (b) to separate the outgoing or discharge stream from the rotating mass. It is to enable this latter function to take place naturally that the opening is made large in area so that this action which is a natural one, may take place without undue interference from solid substances to which the fluid has relative velocity.

The actual sectional areas of the streams entering the drum and also of the discharge stream, are governed by a balance between the forces at work in the fluid itself.

In the construction preferred, the drum is constructed in halves, being split horizontally so that the upper portion may be removed together with the impeller and shaft without disturbing the lower portion which is made fluidtight with the hull.

When the drum is made of rectangular cross section the impeller or paddle is constructed preferably as follows:

A disc of suitable material is secured to the driving shaft by means of a keyway or other recognized device. Blades are slotted into the periphery, the blades making a reasonable clearance with the sides and per-

iphery of the drum and being set transversely to the plane of the disc, after the manner of floats in a radial paddle wheel. The blades are preferably curved so as to present a concave face to the direction of rotation, but they may be curved in any manner desired. The blades may be six in number or any convenient number may be fitted. When the drum is made elliptical in form, the impeller may be constructed as described; but, if desired, it may be constructed with flat or slightly curved blades with parallel sides, each blade having a parallel width, equal approximately to the width of the opening in the drum at the periphery.

Any convenient number of blades may be employed consistent with structural consideration, four being preferred.

When the shaft is rotated the propeller commences to draw in fluid from the direction ahead of the ship, accelerates it during one orbit of the vortex and discharges it in a rearward direction with increased velocity, the reaction resolving through the impeller, into a horizontal thrust on the bearings, driving the ship forward. Direct reversibility is obtainable by reversing the direction of rotation of the impeller shaft.

I shall now describe the methods by which the propeller may be made reversible whilst the direction of rotation of the driving shaft remains unaltered.

To the drum arranged as described is added a tube or duct leading from the portion of the periphery where the direction of the rotating fluid is opposite to the direction of discharge, to the stream line body described and ending in a jet or mouthpiece, facing forwards or substantially forwards. A second drum or portion of a drum, or shoe, is provided which fits concentrically into the first drum and is capable of rotation therein. This inner drum is suspended on trunnions projecting outwards from its sides, and means are provided for its rotation through any desired angle. The inner drum has an opening of larger area than that of the outer drum, so that when the openings in the two drums register, that of the inner drum extends around a greater arc of the outer drum than is represented by the extent of the opening therein. If the inner drum is rotated, during each revolution it carries out the following functions:

1. The opening in the outer drum is unaltered, since the opening in the inner drum registers therewith, the extra extent of the opening in the inner drum being overlapped by the sides of the outer drum. The propeller, therefore operates, driving the ship ahead.

2. The opening of the outer drum is closed by the inner drum being turned so that this opening is closed by the solid portion of the inner drum. The ship therefore stops, and

the prime mover is relieved of any load in excess of that required to overcome the frictional resistance of the vortex and of the impeller shaft bearings.

- 5 3. When the opening in the inner drum registers with the tube or reverse outlet described, the extended portion of the opening of the inner drum registers with the inlet portion of the opening in the outer drum, reversal therefore takes place through the fluid flowing through the reverse outlet in the ahead direction.

- 10 4. When the opening in the inner drum registers equally with both the opening of the outer drum and the astern opening thereof giving equal reactions in the ahead and astern directions. In this condition, the thrusts being balanced the ship remains stationary with the prime mover under full 20 load.

- 15 It will be seen from the foregoing that by rotating the inner drum, any of these conditions, and any condition lying between them, can be obtained, that is to say, that if, 25 for instance, two propellers are fitted, one on either side of the hull and driven by a single shaft rotating in one direction only and at constant speed a full manœuvring power as in the case of a twin screw installation, is obtainable.

- 30 In special cases in which shallow draught is of the greatest importance, a recess may be built in the hull and the propeller carried therein. In such cases, reversal may be effected either in the manner described, or by means of a triangular block fitted under the out-let of the drum. This block would be arranged so that it could be slid horizontally in such manner as to deflect the out-going stream from an astern to an ahead direction.

For use in weedy waters grids may be fitted over the intake holes and these may be made detachable.

- 45 In the construction according to Figs. 1^a to 4, a drum *b*, constructed of any suitable material is fitted in the bottom *a* of the vessel, so that, as will be seen, its major portion is within the vessel whilst its minor, 50 and under portion, projects below the bottom of the vessel and into the water. The drum has (see Fig. 3) curved sides and is somewhat elliptical in cross section. In the interior of the drum is an impeller consisting of four blades *m* mounted on the central boss *l*¹ of the shaft *l* which latter is driven in any suitable and convenient manner from a prime mover which may be a motor or a steam engine, as found most suitable.

- 55 60 A portion of the periphery of the drum at the underside thereof is removed as shown at *p*, *p*¹, Figs. 1^a and 2 so as to leave a gap or opening *k*. In each side of the drum is an opening *j* of somewhat elliptical shape 65 and these lateral openings constitute the wa-

ter inlets and, as will be seen, they are located between the periphery and the centre of the drum. The opening *k* constitutes the outlet for the water when the vessel is being driven forward. As the impeller revolves 70 water is constantly admitted as two converging streams through the lateral openings *j* and moving together pass around the interior of the drum, being finally expelled as a single and intermediate stream 75 through the peripheral opening *k*. If so desired the parts *b*¹ (see particularly Fig. 3) separating the openings *j* from the opening *k* may be cut away along the dotted lines *j*¹, *j*², so as to form one large continuous opening from side to side which would serve both as the water inlet and outlet. A stream line body *e* is provided at the underside of the drum at its forward end and likewise a stream line body *g* at its rearward end the stream line bodies being shaped as shown at Figs. 1 and 2.

80 The drum is preferably provided with strengthening plating *f* at the front.

When it is desired that the vessel should be capable of reversal without reversing the prime mover, the front of the drum is provided with a duct *c* having a grid *d* at the mouth thereof which faces forwards as shown at Figs. 1^a and 2. As will be seen the curved extension *b*¹ of the drum periphery may form the top of the duct *c* whilst the correspondingly curved part *e*¹ of the stream line body *e* may form the bottom of the duct. The curve or sweep of the duct is such as to suit the discharge from the impeller.

85 In order that a reverse drive can be given without changing the direction of rotation of the impeller there is mounted concentrically within the fixed drum *b* a second movable drum *h* which can turn freely on the bearings *s*, *s*¹, the drum being provided with a bevel gear drive *q* rotatable by means of a shaft *r*, so that, by turning the shaft by hand or by power, as preferred, the drum can be turned relatively to the fixed drum *b* more, or less, as desired. The movable drum *h* has a gap *o* in its periphery corresponding to the gap *k* of the fixed drum and has also in each side thereof, a large opening *i* and parts of these openings when the drum is in the position shown at Fig. 1^a register with the openings *j* in the outer drum thereby permitting the water to pass 100 through both drums. It will be seen at Figs. 1^a and 4 whilst the openings *j* are somewhat elliptical in shape the openings *i* whilst partially corresponding to the openings *j* are 105 much longer.

110 When the drum *h* is turned to a position so that the openings *o*, *k*, and *i*, *j*, register, whilst the duct *c* is closed as shown at Fig. 1^a, then the apparatus is in position for 115 propelling the vessel ahead, whereas, when 120

the drum h is turned to the position shown at Fig. 4, so that the gap k is closed, the duct c uncovered and the openings i, j , are only partially opened then the apparatus is in position for driving astern.

When the drum h is in the position shown at Fig. 1^a the openings i, j , serve as inlets for the water (see arrow 6) whilst the openings o, k , form the outlet for the same the water being ejected astern (see arrow 7) with the result that the vessel is driven forward: whereas, when the drum is turned to the position shown at Fig. 4 the water enters through the partial openings i, j , (see arrow 8) and is ejected through the gap o and discharged by the duct c ahead (see arrow 9) with the result that the boat is driven astern. The mere turning of the drum h is sufficient without reversing the impeller which continuously revolves in the same direction.

The impeller shown at Figs. 1 to 4 is of simple construction and consists of four straight blades or paddles m fitted on the boss b^1 of the shaft l .

In many cases it is preferred to have two hydraulic propellers fitted in the vessel and these may be arranged in the manner shown at Fig. 3 the two impellers being driven in conjunction by means of a common shaft l . If desired however the two impellers may be driven by separate shafts.

The apparatus as shown at Figs. 5 to 8 has a single impeller located within the drum b fitted centrally at the bottom of the vessel. There are two downwardly inclined intakes n, n^1 , one at each side of the drum these intakes communicating with the interior of the drum by the inlets t , located between the centre of the drum and its periphery, and with the sea by projecting through the bottom of the vessel forward of the drum. The periphery of the drum has a curved enlargement b^5 which forms a discharge outlet.

In advance and below the drum is a casing x with floor x^1 and opening x^2 therein. The casing is made with a channel which constitutes a discharge outlet r and within this channel works a reversing block u . The block is hollow and of triangular shape with two curved upper sides u^1, u^2 , and flat base which can slide along the floor x^1 . The casing has a curved plate x^3 at the end of the channel this plate corresponding to the side u^2 of the block. The block can be moved from the position shown in full lines to that shown in dotted lines and vice versa by means of the lever v links v^1, v^2 and pin v^3 . When the block is in the position shown in full lines, Fig. 5, the discharge is directed astern through the opening r (see arrow 4) so as to propel the ship forward, whereas, when the block is shifted to the dotted position Fig. 5, the discharge takes place, (see

arrow 5) through the opening x^2 and the vessel is driven astern.

The impeller is shown as provided with four curved blades secured to the rectangular boss b^1 of the driving shaft l .

In the arrangement shown, which is suitable for small craft, the drum b , has a screw plug w which can be removed when required to give access to the interior of the drum for cleaning or other purpose.

The arrangement shown at Figs. 1 to 4 gives greater efficiency than that shown at Figs. 5 to 8 as there are no intakes n, n^1 and, consequently less frictional losses and the rotatable drum also obviates the use of the sliding block. When the parts b^1 are cut away so as to make the same opening serve for both inlet and discharge it simplifies the construction.

It is obvious the drum h may be substituted by a partial drum or shoe or equivalent if so desired the partial drum or shoe being movable within the main drum in the same manner as the drum h .

The main advantages of my improved system of propulsion are as follows:—

As there is no attempt to convert velocity head into pressure head, as in the case of a centrifugal pump, less space is occupied, and less fluid has to be carried within the hull of the ship and losses due to such conversion are eliminated.

The saving of all frictional losses due to piping, as from the inlet to the impeller and from the impeller to the discharge outlet as in other systems and also the saving of frictional and eddy making losses due to the use of guide blades.

Direct use is made of the rotational velocity given to the fluid by the impeller, without any further interference or conversion as in other systems.

The incoming streams take substantially one change of direction only in becoming part of the vortex obtaining in the drum instead of dividing into spirals in all directions, as in the case of the usual pump with central axial feed.

The whole or part of the apparatus can be carried outside the hull of the vessel.

The only conversion from pressure to velocity taking place in my system is brought about gradually by the mixing of the incoming streams with the vortex in the drum.

Having now fully described my invention what I claim and desire to secure by Letters Patent is:—

1. A fluid propeller comprising a casing and an impeller mounted for rotation in said casing so as to allow free circulation of fluid therein, said casing having inlet openings disposed in the opposite side walls between its centre and circumference on one side only of the impeller axis and also having a tangential discharge opening in its

- peripheral wall in the same radial plane as said inlet openings, whereby, upon rotation of the impeller, a fluid vortex is formed in the casing fed by streams of fluid entering in the direction of rotation of said impeller through said side inlet openings, the streams finally merging into a single stream discharged tangentially through said discharge opening.
2. A fluid propeller comprising a casing of substantially elliptical cross section and an impeller mounted for rotation in said casing so as to allow free circulation of fluid therein, said casing having substantially elliptical inlet openings disposed in the opposite side walls between its centre and circumference on one side only of the impeller axis and also having a tangential discharge opening in its peripheral wall in the same radial plane as said inlet openings, whereby, upon rotation of the impeller, a fluid vortex is formed in the casing fed by streams of fluid entering in the direction of rotation of said impeller through said side inlet openings, the streams finally merging into a single stream discharged tangentially through said discharge opening.
3. A fluid propeller comprising a drum having inlet openings disposed in the side walls between its centre and circumference on one side only of the impeller axis and also having two discharge openings in the peripheral wall one of which openings is in the same radial plane as said inlet openings, means for controlling said discharge openings so that when one is opened the other is simultaneously closed, an impeller rotatably mounted in said casing so as to allow free circulation of fluid therein and means for effecting rotation of said impeller.
4. A fluid propeller comprising a drum having inlet openings disposed in the side walls between its centre and circumference on one side only of the impeller axis and also having discharge openings in the peripheral wall, a second drum concentrically mounted within the first and having elongated side openings and also a peripheral opening, means for turning said inner drum to control said tangential discharge openings in the outer drum, and an impeller mounted for rotation within said drums so as to allow free circulation of fluid therein.
5. The combination with a vessel, of a fluid propeller comprising a drum fitted in the bottom of the vessel with a part exposed to the fluid medium surrounding the vessel, said drum having fluid inlet openings in the opposite sides disposed in said exposed part at a position between the centre and the circumference and also having a discharge opening in the peripheral wall in the same radial plane as the inlet openings, an impeller mounted within the drum so as to allow the fluid free circulation therein and means for effecting rotation of said impeller.
6. The combination with a vessel of a fluid propeller comprising a drum fitted in the bottom of the vessel with its axis horizontal and with a part exposed to the fluid medium surrounding the vessel, said drum having fluid inlet openings in the opposite sides disposed in said exposed part at a position between the centre and the circumference and also having discharge openings in the peripheral wall one of which is in the same radial plane as the inlet openings, means for controlling said discharge openings so that when one is opened the other is simultaneously closed, an impeller rotatably mounted in the drum so as to allow the fluid free circulation therein, and means for effecting rotation of said impeller.
7. The combination with a vessel of a fluid propeller comprising a drum fitted in the bottom of the vessel with a part projecting therebelow, said drum having inlet openings in the opposite sides disposed in said exposed part between the centre and the circumference and also having peripheral discharge openings, a second drum concentrically mounted within the first, gearing for turning said inner drum to control said discharge openings and an impeller rotatably mounted in said drums.
8. In a vessel a fluid propeller comprising an elliptical drum fitted in the bottom of said vessel with its axis substantially horizontal and with a part exposed to the fluid medium surrounding the vessel, said drum having inlet openings in the opposite side walls located in said exposed part between the centre and the circumference and also having a peripheral discharge opening in said part intermediate said inlet openings, and an impeller mounted for rotation in said drum so as to allow free circulation of the fluid therein.
9. In a vessel a fluid propeller comprising a drum fitted in the bottom of said vessel with its axis substantially horizontal and with a part exposed to the fluid medium surrounding the vessel, said drum having inlet openings in the opposite side walls located in said part between the centre and the circumference and also having peripheral discharge openings in said part one of which is in the same radial plane as the inlet openings, means for controlling said discharge openings so that when one is open the other is closed, an impeller rotatably mounted in the drum and means for rotating said impeller.
10. Means for effecting fluid propulsion of a vessel, comprising two similar drums fitted in the bottom of the vessel on opposite sides with parts exposed to the surrounding fluid medium, each of said drums having inlet openings in its opposite side walls dis-

posed in said exposed part between the centre and the periphery and also having a peripheral discharge opening in said part, an impeller rotatably mounted in each drum

5 so as to allow free circulation of fluid therein, and means whereby said impeller can be operatively connected with a suitable driving source.

11. Means for effecting fluid propulsion
10 of a vessel, comprising two similar drums fitted in the bottom of the vessel on opposite sides with parts exposed to the surrounding fluid medium, each of said drums having inlet openings in its opposite side walls dis-

15 posed in said exposed part between the centre and the periphery and also having pe-

ripheral discharge openings in said part, an inner drum concentrically mounted in each of said first mentioned drums, gearing for turning each inner drum to control the discharge openings therein, impellers rotatably mounted in the drums so as to allow free circulation of the fluid therein, and mechanism connecting the impellers with a suitable

20

25

driving source.

In testimony whereof I affix my signature in presence of two witnesses.

DONALD VIVIAN HOTCHKISS.
